UNITED STATES PATENT OFFICE

BROOKS NOTTINGHAM ANDERSON, OF NORFOLK, VIRGINIA

MATERIAL-TRANSFER MECHANISM

Application filed June 11, 1930. Serial No. 460,458.

This invention relates to mechanism for transferring material from beneath cars having hopper bottoms to elevators or other means employed for conveying the material to 5 the point of storage.

Heretofore different types of unloaders in the form of conveyors have been used, but it has been necessary to move them out of position and back again into position before and 10 after the shifting of a car. This has resulted in considerable loss of time. It has also produced undesirable breakage of materials, such as soft coal, due to the excessive weight to 15 which the moving parts of the machine have been subjected during the unloading operation.

It is an object of the present invention to provide a simple and compact mechanism onto 20 which material will be discharged when the bottom doors of a car are opened, this material flowing by gravity off of the mechanism and onto the conveying means adjacent thereto until a relatively small pile is left on the apparatus whereupon said apparatus is set 25 into motion for the purpose of transferring the material left thereon to the conveying mechanism, at which time said material offers but slight resistance to the transfer thereof and, consequently, danger of breakage of the 30 lumps of material is reduced to the minimum.

It is a further object to provide a mechanism which can be installed in a relatively shallow pit formed beneath the track, it being 25 possible readily to transfer the mechanism from one pit to another when desired.

With the foregoing and other objects in view which will appear as the description proceeds, the invention resides in the combination and arrangement of parts and in the 30 details of construction hereinafter described and claimed, it being understood that changes in the precise embodiment of the invention herein disclosed may be made within the 35 scope of what is claimed without departing from the spirit of the invention.

In the accompanying drawings the preferred form of the invention has been shown.

In said drawings

50 Figure 1 is a plan view of the apparatus.

Figure 2 is a horizontal section on the line 2—2, Figure 3.

Figure 3 is a central vertical section through the apparatus.

Referring to the figures by characters of 55 reference, A designates the track on which a car B is adapted to travel, it being understood that the car is of the type having bottom doors adapted to open downwardly when it is desired to deliver bulk material there- 60 from.

A pit 1 is adapted to be formed between the rails of the track A, this pit being suitably lined with concrete if so desired. The pit is adapted to receive a casing 2 formed of metal 65 which, when in position, can be supported by sills 3. A top plate 4, end plates 5, and a bottom plate 6 constitute walls of the casing.

Journalized in the corner portions of the casing 2 are shafts 7, 8, 9, and 10, carrying 70 sprockets 11 on which are mounted endless chains 12 to which are secured relatively small cross cleats or drags 13. These chains and drags co-operate to form an endless conveyor. It is to be understood that, if preferred, a belt of rubberized fabric or other suitable material can be substituted for the chain conveyor illustrated. This conveyor is adapted to travel along the outer faces of the 75 plates 4, 5, and 6 in the direction indicated by the arrows. When the casing 2 is in the pit 1 the top portion thereof will be well above the top of the track and extends close to the inner sides of the rails.

For the purpose of actuating the drag 80 chains an electric motor 14 is located within the casing 2 and transmits motion through chain and sprocket mechanism 15 to a counter shaft 16 which, in turn, transmits motion through chain and sprocket mechanism 17 to another counter shaft 18. A sprocket 19 rotates with shaft 18 and is adapted to drive a chain 20 mounted on a sprocket 21 secured to shaft 7. The chain and sprocket 85 mechanisms 15 and 17 constitute speed reducing means.

As before explained this transfer mechanism is adapted to be placed in the pit 1 and the upper portion of the drag chains will move transversely of the track in a plane 100

above the rails. Cover plates 22 can be secured over the casing so as to lap the drag chains and prevent bulk material from falling into the pit. The car to be emptied is placed in position over the pit so that when its bottom doors are swung downwardly the bulk material in the car will be directed onto plate 4 and between and over the drags 13 thereon. As the material is piled in this manner it will flow over one or both of the rails 10 onto one or more conveyors adjacent to the track which are used for carrying the material to the point of storage. It has been found in practice that all but approximately five tons of coal, for example, will flow laterally in this way, leaving only a relatively small pile of about five tons resting on the drags and on the plate 4. The motor 14 can be then started so as to actuate the chains through the speed reduction mechanism. 20 This will cause the drag to carry the material laterally and deliver it over one of the rails onto the conveying means.

As the transfer mechanism, while in operation, is relieved from the excessive weight of bulk material, the movement of the drag through the material will not result in excessive breakage. Should any of the material fall into the pit, it would not interfere with the operation of the mechanism which is of sufficient strength to carry around with the drags any such material which might block the path thereof.

Obviously pits may be located wherever desired, and by means of suitable hoisting mechanism, a single transfer apparatus such as herein described, can be shifted from one pit to another. Ordinarily, however, the apparatus will remain undisturbed and loaded cars will be brought to position one at a time above each pit, each car being first unloaded through one set of opened doors after which another set of doors is brought to position above the pit and opened.

The structure illustrated can of course be modified within the scope of the claims for the purpose of meeting any special conditions under which it is to be used.

What is claimed is:

1. Transfer mechanism for use beneath a car having a bottom outlet, including a casing adapted to be seated in a pit and to extend above and between the rails of a track, endless dragging means movable around the casing transversely of the track, said means and the casing being adapted to support a pile of bulk material delivered thereonto, the casing constituting means for guiding surplus material over the rails of the track, and means within the casing for actuating the dragging means for delivering transversely from the top of the casing the material of the pile remaining on the casing subsequent to the gravitation of loose material from the casing.

2. The combination with a track having a pit thereunder, of a casing seated within and extending above the pit, the top of the casing being above the track, endless dragging means extending around the casing and movable transversely of the track, and means in the casing for actuating the dragging means. 70

3. The combination with a track having a pit therebelow, of a casing in the pit projecting above the top of the track for receiving bulk material delivered from a car thereabove and shedding surplus material laterally over the rails of the track, dragging means extending around the casing, a motor in the casing, and means actuated by the motor and located in the casing for operating the dragging means to deliver laterally over a rail of the track bulk material supported above said means. 75

4. The combination with a track having a pit thereunder, of a plate supported between and above the rails of the track for receiving bulk material delivered downwardly thereonto and shedding it laterally over the rails to leave a relatively small pile, endless dragging means extending over the plate transversely of the track and into the pit, and means within the pit for actuating the dragging means to deliver laterally over one of the rails the bulk material remaining on the plate. 80

5. The combination with a track having a pit thereunder, of endless dragging means extending into the pit and movable transversely of the track above and between the rails, and means within the pit and surrounded by the dragging means for actuating said means to deliver laterally over one of the rails material deposited on the guiding means. 95

In testimony that I claim the foregoing as my own, I have hereto affixed my signature.

BROOKS NOTTINGHAM ANDERSON.
